UNITED STATES PATENT OFFICE.

SIMON GROSSMAN, OF PITTSBURGH, PENNSYLVANIA.

METAL-BENDING MACHINE.

1,264,062.

Specification of Letters Patent. Patented Apr. 23, 1918.

Application filed September 21, 1916. Serial No. 121,426.

To all whom it may concern:

Be it known that I, SIMON GROSSMAN, a citizen of the United States, residing at Pittsburgh, in the county of Allegheny and 5 State of Pennsylvania, have invented certain new and useful Improvements in Metal-Bending Machines, of which the following is a specification.

My invention relates to improvements in 10 metal bending machines, and is designed particularly for the purpose of bending to desired shape, metallic strips for use in the manufacture of suit cases and particularly for strengthening the cover or lid of the 15 case. It will of course be understood that the strip may be used for other purposes for which it is adapted, the reference herein being only to the specific use to which I am now applying the strip.

20 The invention consists essentially in certain combinations and arrangements of parts including roller couples and their connections, and other devices, as will be herein-after more fully pointed out and claimed.

25 In the accompanying drawings I have illustrated one complete example, omitting the housing of the machine, of the physical embodiment of my invention constructed and operated according to the best mode I 30 have so far devised for the practical application of the principles of my invention, and this construction as illustrated has proven highly satisfactory in actual use.

35 Figure 1 is a top plan view of a bending machine constructed according to and embodying my invention, the housing being omitted for purposes of illustration.

Fig. 2 is a side elevation of the machine of Fig. 1.

40 Fig. 3 is a sectional view of the base and frame of the machine, but showing the rollers and other parts in full.

Fig. 4 is a transverse view of the machine at line 4—4 of Fig. 1.

45 Fig. 5 is a transverse section at line 5—5 Fig. 1.

Fig. 6 is a transverse section at line 6—6.

Fig. 7 is a sectional view at line 7—7

Fig. 1.

50 Fig. 8 is a sectional view at line 8—8 Fig. 1.

Fig. 9 is a sectional view at line 9—9

Fig. 1.

55 Fig. 10 is an enlarged view showing the last roller couple of the machine.

Fig. 11 illustrates the forming core and shows its relation to the rolls of Fig. 10.

Fig. 12 shows the different steps in the formation of the metallic strip starting with the blank or stock strip.

In the preferred embodiment of my invention as illustrated in the drawings I have shown the machine as now used in actual manufacture of the suit-case lid frames, and this machine is supported upon the bed plate 60 or base 1 and includes the two sides or side walls 2, 2. Upon each of these side walls a longitudinal bar is located and indicated as 33, the bolts 4 being employed to attach the bar rigidly to the top edges of the side walls 65 of the machine bed. The machine is preferably power operated through the drive wheel 5 upon which a suitable driving belt is wound, but the flat metallic stock strip or blank A is fed to the machine by an attendant 70 who lays the strip in the guide table 6 at the right of the machine and feeds the strips successively to the machine. The guide or feed table 6 is attached by bolts 7 to an angle plate 8 which is in turn attached 75 to the right or front end of the machine frame by bolts 9.

In order that a clear understanding of the construction and operation of the machine may be gained I will now proceed to describe the steps of formation of the completed article from its first stock strip or blank A to the final stage as shown in Fig. 12. The flat metallic strip is first bent at 80 its edges as indicated at B and B' leaving the body A' flat. These two flanged portions or bent edges of the strip are next turned over to form beads C and C' after which the body portion A' is bent at right angles to form a flange D, and then this 85 flange D is bent to form a curved or rounded flange E. These successive steps are accomplished between the entrance of the metallic strip from the feed table 6 at the front or right end of the machine and the exit of the 90 strip at the left end.

An angle plate 10 formed with a depressed curved face 11 is employed in connection with the feed table 6 to start the flat strip into the machine and a guide roller, preferably of rubber or felt may be used as at 12 to guide the strip to the first roll couple 13—13' which couple forms the two flanges B and B'. The roll couple 14—14' forms 105 couple 15 15' forms the beads C and C', then couple 15 15' forms 110

the beginning of flange D which couple 16 16' completes, and then the couple 17 17' forms the curved flange E. The three rolls 18, 19, and 20 are provided to guide the completed strip at the delivery end of the machine. The rolls forming couple 13 and 13' are formed respectively with enlarged central body portion 21, and the overlapping flanges 22, 22 to turn up the edges or flanges 10 B B'. The beads C and C' are formed between the annular grooves 23 23 of the roll 14 and the enlarged portion 24 of the roll 14', and the initial bend of the flange D is attained through the concave portion 25 of roll 15' and the convex rounded edge 26 of the roll 15. To complete the vertical bend or flange D, the rolls forming couple 16 16' are formed respectively with squared shoulder 27 and squared flange 28, and finally the 20 annular curved groove 29 of roll 17 co-acting with the enlarged portion 30 of the roll 17' turns the flange D to the curved flange E, and the rolls 18 19 20 conform to the shape of the completed strip and deliver it 25 without bending or warping.

In its course through the machine from the receiving end to the delivery end, the strip is guided, first as indicated in Figs. 3 and 5 by four rollers designated 31, 32, 33, 30 34. The first two rollers 31 and 32 are journaled in the frame and are disposed horizontally. These rollers are grooved to conform to the edges B and B' and are spaced apart so the strip may pass between them. The 35 roller 33 is supported beneath the strip, and the upper roller 34 is adjustable so that pressure on the strip may be varied as desired. This roller 34 is journaled at the lower end of a beam 35 which is laterally 40 perforated for passage of the fixed bar or rod 36 extending between the two side walls of the machine frame, and supported between these side walls. An adjusting bolt 37 passes through the beam 35 and is threaded through the supporting bar 36, so that by turning the bolt the beam may be raised or lowered with relation to the bar, thus moving and adjusting the roller 34 carried by the beam.

50 Between the second and third roll couples, a guide block 38 is located and between the third and fourth roll couples a second guide block 39 is utilized, both these blocks having rounded and smooth undersurfaces 55 against which the upper face of the metal strip passes and by which the strip is guided to the next adjoining roll.

In conjunction with the roll couple 17-17' I utilize the guide block 40. Each 60 of these guide blocks are supported from the side walls of the machine frame at an altitude to hold the metal strip in proper horizontal position as it passes through the machine, and the block 40 also is provided 65 with a forming core 41 co-acting with the

roll 17 17'. This core is an integral bar projecting from the block and disposed longitudinally of the machine, and designed to co-act with the groove 29 of roll 17 and shoulder 30 of roll 17' as shown in Figs. 10 70 and 11 to turn the straight flange D into the curved flange E of the metal strip. This is accomplished as the straight flange passes alongside the bar or core 41 and the grooved roll 17 turns the flange over against the core 75 25 as shown. A vertically disposed guide roller 42 is located in proper position to guide the flanged strip and hold it against wobbling as it encounters the core 41, and a guide block 43 located beneath the line of travel 80 of sheet metal strip guides it to the delivery rollers 18 19 20, whence it is delivered over the apron or table 44.

The roll couples are driven from the drive wheel 5 and drive shaft 12' through the 85 train of gears 45 46 and 47, the first gear being on the drive shaft 12' and the succeeding gears 46 and 47 on roller shafts or axles 48 and 49 respectively, which are journaled in the side walls of the frame. 90

The first three roll-couples are operated by gear-couples comprising respectively upper and lower gears 50 50', 51 51', and 52 52', an idler 53 being journaled on the bar 36 between gears 50 and 51, and a lower 95 idler 54 being located between gears 51' and 52' to transmit motion to these couples. The first couple includes axles 55 55', the second couple shaft 12' and axle 56 and the third couple includes its axles 57 and 48; the 100 fourth couple shafts 49 and 58, and the fifth couple designated in Fig. 9 has shafts 59 and 59'.

The fourth and fifth gear couples comprise respectively gears 60 60' and 61 61' 105 and in addition the shaft 59' has a gear 62 which meshes with the idler 63 (Fig. 2) which in turn meshes with the gear 64 to revolve the delivery roll 20. The delivery roll 18 has a driving gear 64 driven by idler 65 110 from the gear 61 of the couple 61-61'. Through the above described gearing the roll couples are revolved in unison and the metal strip is carried from the receiving end of the machine to the delivery end out 115 over the apron or table 44.

The upper members of the couples are each journaled in a pair of bearing blocks designated as 65 or 65' and these blocks are located in recesses or seats provided for 120 them in the upper edges of the side walls of the machine, a piece of rubber, or other resilient member 66 being located in the bottom of each seat below its block and the two series of blocks are held in position by the two 125 side bars 3 and 3'. In order to adjust the upper rolls to the lower rolls, and thus adjust the roll members to the metal strip, I employ two series of set screws 67 67' provided with lock nuts 68 68' and passed through 130

threaded perforations in the bars 3 and 3'. In Fig. 7 specifically it will be seen that these bolts bear upon the upper surface of each of the blocks, and when the bolts are turned down the blocks are forced down against the resiliency of the rubber block 66. In this manner the bearing blocks may be adjusted individually and independently, but are all held collectively by the two side bars 3 and 3'.

Oil holes 67² 67³ are provided in the side bars 3 3' and these holes convey oil to the grooves 68² in the sides of the bearing block from whence the oil may flow through duct 69 in the side bearing walls of the frame to lubricate the bearings of the lower members of the roll couples. Other oil holes as 70 (Fig. 1) may lead directly to the bearings of the upper members of the couples.

In actual use I employ a housing for the machine, but in order to clearly illustrate the machine I have omitted the housing. The feed table, it will be understood is as long as the machine in order to accommodate the metal strips of various lengths and the strip (which may be fed from a coil if desired) is pushed under the guide block 11 until it is caught between the rolls of the first couple and then passes without further attention from the operator through the successive roll couples and is delivered, a completed article, at the delivery end of the machine. It will be understood that the machine may be operated in positions other than that illustrated, as for instance the rolls may stand upon vertical axes. The roll couples may be adjusted to roll heavy or light metal, and the delivery rolls may be adjusted to straighten, bend or curve the strip as it is delivered from the machine. By the utilization of my machine I am enabled to increase the output, shorten the time of manufacture, and reduce the labor required, as compared with hand made strips, thus reducing the cost of making these strips.

What I claim is:—

1. A machine of the character described comprising, in combination, successive roll

couples, whereof the first are adapted to 50 bend the longitudinal edges of a flat strip at right angles, succeeding rolls adapted to roll said edges upon the strip, other succeeding rolls adapted and arranged to bend one edge portion of the thus formed strip with a 55 right angle wing, and further succeeding rolls adapted to laterally and inwardly curve said wing.

2. A machine of the kind described, comprising a series of aligned rotary roll couples 60 having their working faces formed to longitudinally receive a sheet fed forward and between the same and to bend the longitudinal edges of the sheet, the first roll couple being formed to bend the edges of the sheet at 65 right angles thereto, the second roll couple being formed to roll said right angularly bent edges upon the sheet, succeeding pairs of roll couples being grooved to bend the thus formed sheet with a right angle wing 70 on one edge portion thereof, and other succeeding roll couples being formed to laterally and inwardly curve said wing, and guide means for the sheet between said roll couples.

3. A machine of the character described, comprising, in combination, successive roll couples, whereof the first are adapted to bend the longitudinal edges of a flat strip at right angles, succeeding rolls adapted to 80 roll said edges upon the strip, other succeeding rolls adapted and arranged to bend one edge portion of the thus formed strip with a right angle wing, further succeeding rolls grooved to laterally and inwardly curve 85 said wing, and a flat guide plate in the advance of said last mentioned roll couple and having a rearwardly extending core projecting in the groove of the roll couple, said core being formed complementary with said 90 groove.

In testimony whereof I affix my signature in the presence of two witnesses.

SIMON GROSSMAN.
